UNITED STATES PATENT OFFICE.

JOSEPH BOURDAS SMITH BOOTH, OF SIDCUP, ENGLAND.

CARBURETER.

1,362,468.

Specification of Letters Patent. Patented Dec. 14, 1920.

Application filed June 21, 1918. Serial No. 241,279.

To all whom it may concern:

Be it known that I, JOSEPH BOURDAS SMITH BOOTH, a subject of the King of Great Britain, residing at Sidcup, Kent, England, have invented certain new and useful Improvements in Carbureters, of which the following is a specification.

This invention relates to carbureters and has for its chief object to provide mechanism for automatically controlling the quantity and quality of the explosion mixture to develop and maintain an engine speed within the limits of the power of the engine as dictated and determined by the driver through appropriate mechanism.

According to the present invention the air supply or inlet and the mixture outlet or delivery to the engine or motor are regulated by mechanism automatically operated to determine a quantity and quality of mixture required to develop and maintain an engine speed as dictated by a device which is under the control of the driver. In carrying the invention into effect the quality and quantity of mixture required for all speeds and powers, to be developed, within the limits of the power of the engine, are automatically controlled by regulating the air inlet and the mixture delivery conveniently each by a throttle or similar valve, and these valves are capable of being automatically operated separately, or relatively, and also simultaneously or together by the automatic mechanism. One of the valves is situated around the jet or nozzle or on the air inlet side of the carbureter and the other is situated on the engine side of the carbureter. Conveniently the mechanism which governs or controls the movements of the two valves comprises pistons which are operated by fluid circulated by a fluid-pressure pump that is driven from or by the engine supplied by the carbureter.

The fluid delivered by this controlling pump passes into a cylinder in which one of the pistons is situated and moves the piston which opens or effects or permits the opening of the throttle valve controlling the air inlet and this movement may also operate the throttle valve on the engine side of the carbureter. When this primary piston has been moved a certain distance, an outlet valve from the cylinder is opened and a portion of the fluid passes to another cylinder, in which the other or secondary piston is situated, and effects the movements of this piston. This movement of the piston in the

second cylinder operates the throttle valve on the engine side of the carbureter, and it may effect the movement of both throttle valves together or relatively to one another. The extent to which the second piston is moved is dependent upon the position of the first piston as determined by the speed at which the engine is running the constant speed required under varying loads as dictated by the device which is under the control of the driver. The throttle valve controlling the air inlet is primarily moved by its controlling piston in direct proportion to the speed of the engine, since the pump driven by the engine delivers fluid directly to the cylinder of the piston, and the throttle valve on the engine side of the carbureter is moved by the piston working in the corresponding cylinder to maintain the speed dictated by the driver since the movement of the controlling piston is determined by the amount of fluid entering the cylinder and permitted to act on the piston in accordance with the position of the control device or valve as dictated by the driver.

Referring to the accompanying drawings:

Figure 1 is a section diagrammatic elevation of one form of control mechanism embodying the present invention.

Fig. 2 is a similar view of a modified arrangement.

Fig. 3 is a sectional elevation of another modified construction.

Fig. 4 is a plan of Fig. 3.

Fig. 5 is an end elevation of Fig. 4.

Fig. 6 is a sectional elevation on the line 6—6 of Fig. 5.

Fig. 7 is a sectional view of the two throttle valves.

Fig. 8 is a perspective view of the arrangement illustrated in Figs. 3 to 7, and Figs. 9 and 10 are detailed views showing the lever connections between the valves and the pistons in different positions.

A is the throttle valve controlling the air supply to the nozzle: B the throttle valve controlling the mixture to the engine, and C is the primary piston which is first acted upon by the fluid from the pump: D the secondary piston which is acted upon by the fluid from the cylinder of piston C: E is the pump, and F the valve which is under the control of the driver.

Referring first of all to the arrangement shown in Fig. 1.

The valve A is in the form of a bell-shaped

structure and is disposed over the jet or nozzle G situated in a conduit or passage G¹. When the engine is not running this valve is in its closed down position. Air enters 5 the conduit G¹ at g and passes under the edge of the valve A in quantity depending upon the extent to which the valve A is moved by the piston C.

The pump E, which is preferably a gear 10 pump, is driven through a shaft e and gearing e¹ from a moving part of the engine and is situated in a fluid containing casing E¹ and delivers the fluid under the piston C causing it to move in its cylinder.

15 As the pump is driven from the engine the amount of fluid delivered to the cylinder c of the piston C is directly dependent upon and proportional to the speed of the engine, so that the extent of opening of the valve 20 A in this case is directly dependent upon the speed at which the engine is running.

The fluid passes from the cylinder c by a valve-controlled port c¹. In the present embodiment the piston C acts as a valve for 25 which purpose it is formed with a cut away or tapering part c². The higher the piston C is raised in the cylinder in accordance with the speed of the engine, as aforesaid, the greater is the extent to which the port 30 c¹ is uncovered and the greater is the quantity of fluid which passes from the cylinder by the port c¹ to the cylinder d in which the secondary piston D is situated.

The piston rod C¹ of the piston C is connected to a lever A¹, one end of which, in 35 the present example, is fulcrumed to a stationary support e² at a. The other end of the lever A¹ is connected to the valve A by a link A².

40 The fluid circulated by the pump and passing from the cylinder c by the port c¹ and depending in quantity on the height to which the piston C has been operated, is led by a conduit E³ to the cylinder d.

45 The piston D has a piston rod D¹ which is connected to a lever B¹ one end of which is fulcrumed to a stationary part at a and the other end is connected by a link B² to an arm B³ on the second throttle valve B, 50 which is situated as shown in the supply pipe G on the engine side of the carbureter. The valve B, when the engine is not running, is fully open as indicated in Fig. 1.

55 Communicating with the cylinder d and with the well in the pump chamber is a port F¹ in which is situated the control valve F. The fluid entering the cylinder d from the conduit E³ tends to raise the piston D, and the extent to which the piston 60 D is raised and therefore the extent to which the throttle B is operated depends upon the relative positions of pistons C and D as determined by the speed of the engine and the position of the control valve 65

F which is operated by the driver through suitable mechanism. The fluid passing through the valve F returns to the chamber and is again available for the pump. The driver closes or opens the valve F to a greater 70 or less degree in accordance with the speed at which he desires or requires the engine to run. Should the quantity of fluid entering the cylinder d be greater than can pass through the controlling valve F the piston 75 D will be moved and cause a closing down of the valve B thus reducing the demand on the carbureter and a reduction of engine speed. The reduced engine speed will result in less liquid being delivered by the 80 pump to the cylinder of piston C so that the piston C will move backward by gravity or by a spring and a partial closing of the controlling throttle A take place. This setting of the valve F has thus an immediate effect upon the position of the throttles 85 A and B and thus the quantity and quality of the mixture supplied by the carbureter are automatically controlled by the valves A and B. 90

In the modified construction illustrated in Fig. 2 the lever A¹ which is operated by the piston C and is connected to the throttle A, instead of being fulcrumed to a stationary part as described with reference to Fig. 95 1, is fulcrumed to the lever B¹ which is operated by the piston D connected with the throttle B.

The valve A is thus opened by the movement of the primary piston C, as in the 100 previously described arrangement, and thereafter may be moved to a certain extent by the movement of the piston D since any movement of the piston D will be transmitted to lever B¹ thence to lever A¹ which, 105 turning on its pivotal connection a² with the piston rod C¹ operates the valve A relatively to the valve B.

The throttle valve A is so set by the first movement of the primary piston C that 110 the engine suction at all speeds produces a correct mixture with the minimum throttling effect thus determining the highest power the engine is capable of exerting. This latter, being much greater than would be required normally, would result in a rapid increase of speed up to maximum but for the action of the secondary piston D, the position of which is determined by the 115 excess of fluid pumped beyond that permitted to escape by the valve F, and this piston D acting upon the valves B and A through levers B¹ and A¹, dictates or determines the speed of the engine in accordance with the amount of opening of the 120 valve F. The amount of fluid passing through the valve F determines the amount which will act on the piston D. Should this be an excess of fluid pumped, the 125 amount in excess operates to move the pis- 130

ton D thus closing down practically the two throttles A and B; should the engine speed fall, the amount of fluid passing through the valve F, being in excess of the quantity pumped, the secondary piston D will be moved back by gravity or by a spring, thus opening both throttle valves A and B the amount required to raise the engine speed and again strike and maintain a balance between the amount of fluid pumped and the amount permitted to escape by valve F.

This arrangement possesses advantages over the arrangement described with reference to Fig. 1 since it takes cognizance of the fact that for a given speed of the engine various degrees of power may be required and by coupling the lever A¹ to the lever B¹ of the piston D, the valve A is directly controlled not only by the speed of the engine through pump E and piston C but also directly by the movements of the piston D in accordance with the amount of fluid passing to the cylinder d and the degree of opening of the valve F determined by the driver. For example, as applied to a motor vehicle, when the vehicle is descending a hill and is assisted by gravity, the speed of the engine may be maintained or increased but the demands on the carburetors are not increased. The valve B will be closed down according to the amount of the fluid entering the cylinder d and the piston C will be in a position to hold the valve A open, thus unless the means above described for controlling the valve A are provided a wrong quality of mixture will be supplied. By connecting the valve A with the lever B¹ of the piston B, however, whenever the valve B is closing down, in conditions such as referred to, a corresponding closing down of valve A will take place, irrespective of its movements under the influence of the piston A.

Referring now to the arrangement illustrated in Figs. 3-10, the two throttle valves A and B are in the form of segments rotatably mounted upon coaxial shafts A¹¹, B¹¹ respectively, situated in a casing G¹⁰ surrounding the jet or nozzle G and these shafts are connected with or coupled with their respective operating mechanism.

The pistons C and D are disposed in their cylinders which are arranged horizontally in a block disposed in the pump casing E¹.

According to this embodiment of the invention the valves A and B are both in their closed down position when the engine is not running.

The throttle valve A, which, as already stated, controls the air inlet opening g is not positively connected with the piston C as in previously described arrangements, but the movements of piston C are utilized to position a stop C³⁰ which regulates the extent

of opening of the valve A according to the speed of the engine. The stop C³⁰ is mounted on an arm C⁵ on the upper end of a sleeve C²⁰ which is rotatably mounted on the shaft A¹¹. The rod C⁴ of piston C is connected to another arm C¹⁰ on the sleeve C²⁰ and secured to a third arm C²² on the sleeve C²⁰ is one end of a spring C⁴⁰, the other end of which is fixed to a stationary member in the casing. This spring is so arranged that it opposes the turning of the sleeve C²⁰ under influence of the piston C.

Pivotedly connected to a boss on the arm C⁵ concentric with the stop C³⁰ is one end of a link A¹⁰ to the other end of which is pivoted a link A⁴⁰ which is connected with one end of a lever A²⁰ which lever is secured intermediate its ends to the upper end of the shaft A¹¹ to which the valve A is secured. The end of the lever A²⁰ opposite to that to which the link A⁴⁰ is connected has attached to it one end of a spring A⁵⁰, which is of less power than the spring C⁴⁰ and has its other end secured to a fixed point. Between the points of its attachment to the spring C⁴⁰ and the shaft A¹¹ the lever A²⁰ bears against the stop C³⁰.

Pivoted to the link A¹⁰ coaxially with the link A⁴⁰ is one end of a link B³⁰, the other end of which is adjustably secured to one end of a lever B²⁰ which is fixed intermediate its ends to the shaft B¹¹ of the valve B and the other end of this lever B²⁰ is pivotally secured to the rod D¹ of piston D.

Through the connections of the links A³⁰, A⁴⁰ and B³⁰ with the sleeve operated by the piston C on the one hand and with the levers A²⁰ and B²⁰ connected respectively with the valves A and B, both valves can be operated by the movements of either piston. The links constitute a differential gear so that, if the movement of one piston is checked or opposed by the other, the two valves are moved relatively to each other or to different extents. The link B³⁰ can be adjusted on the arm of the lever B²⁰ so as to vary the effective lengths of the arms of levers B²⁰ and A²⁰ relatively to one another in accordance with the requirements of a particular engine.

In the passage between the two cylinders c and d is situated a control valve C²² which is operated by the movements of the piston C. On the sleeve C²⁰ to which the rod of the piston C is attached, is an arm C²³ carrying a stud to which a lever C²⁴ of the valve C²² is connected by a link C²⁵. This valve is operated in proportion to the extent of travel of the piston C and controls the fluid passing from the cylinder c to the cylinder d.

The valve F by which the driver dictates the speed of the engine, controls as in previous examples, the outlet from the cylinder d. This valve may be constructed as in the previously described arrangements or it

may be of other appropriate form. Preferably, however, it is in the form illustrated in Fig. 6, as in this form the outlet controlled by the valve is automatically varied, 5 within limits, in accordance with variations of pressure due to the variable tension of the spring A^{50} , and thus the valve opening is relative to the position of the lever operated by the driver to set the valve, and the liquid 10 pressure acting on the valve, to maintain a flow corresponding to the position of the control lever. The valve proper f is arranged to work relatively to a seating f^1 and the stem f^2 of the valve is screwed through 15 a block f^3 which is free to slide in a tube f^4 . The block has a spiral groove around its exterior, and the convolutions of the spring rest in this groove so that the block is adjustably connected to a spring f^5 . Normally 20 the block is situated at or about midway of the length of the spring. The tube f^4 is a sliding fit in a casing f^6 and one end of the spring f^5 bears on the upper end of the tube f^4 while the other end bears against the 25 lower end of the casing f^6 . The lever controlled by the driver acts upon the tube f^4 , by depressing which the spring will be compressed and the valve more or less closed, but the spring permits a movement of the 30 valve independently of the controlling mechanism in accordance with the fluid pressure acting upon the valve. When the engine is not running the valves A and B are in the position shown in the drawings.

35 When the engine is turned for starting fluid is immediately forced by the pump E into the cylinder c moving the primary piston C against the action of spring C^{40} and opening the valve C^{22} permitting fluid to 40 pass to the cylinder d of the secondary piston D. The movement of piston C allows the spring A^{50} to act and through the lever mechanism above described the valves A and B will be opened. The two valves move in 45 unison and the piston D moves inward as the fluid in cylinder d passes out by valve F, and this movement will continue until, by the movement of piston C the valve C^{22} is opened to allow a quantity of fluid, equal to that 50 delivered by the pump, to pass to the cylinder d . When this point is reached, the movements of both pistons ceases and the valves A and B are in position to insure the production of a perfect mixture for that 55 speed of the engine. When the engine commences to fire, an increase in its speed takes place resulting in an increased flow of liquid from the pump and a consequent opening of both valves A and B due to the outward 60 movement of the piston C still in such relation to the increasing speed as to produce the largest valve opening that will give a perfect mixture. Unless checked the continuance of these conditions would soon result in the engine reaching maximum speed. 65

But as the delivery of fluid by the pump increases with the increasing speed of the engine, a point is soon arrived at where the amount of fluid entering the cylinder d is greater than can pass through the valve F 70 as then set, and this results in arresting the inward movement of the piston D and checking a further opening of the valves A and B before these two valves will have reached their fully open positions. The engine exerting its maximum power at this point so that its speed will continue to rise, the valve A will be still further opened under action of the piston C, but as the movement of piston D, and therefore valve B, has been 80 checked, by the fluid in the cylinder d , the valve A alone opens further through the liquid in the cylinder c acting on piston C which through the aforesaid link mechanism 85 operates the valve A. The increased speed of the engine finally results in the quantity of fluid entering the cylinder d being in excess of what can pass through the valve F, which moves the piston D outward and operates both valves in a closing direction, the 90 amount of closing being differential on account of the link mechanism. Should greater effort or power be demanded from the engine, due by gradient, increased weight, bad road surface, windage, or other cause, the 95 ensuing loss of speed results in a decreased pump-delivery and the piston D will be moved to further open the valve D while the valve A will also be moved in an opening direction by the movement of the piston C 100 and also by reason of its connection with the piston D. The movements of the two valves will continue to give an increasing volume of mixture to meet the new demand for power until maximum power at the particular dictated speed is attained. Should this speed be reached before the power-demand is met, speed will automatically be reduced as the engine will be overloaded.

On the other hand, if the engine continues 110 to run at a speed greater than that dictated by the driver, independently of the engine effort, for example with a vehicle descending a steep gradient, the piston D will continue to open valve B until a passage B^{50} in the 115 valve establishes communication between the atmosphere through a by-pass B^{60} and the conduit between the carburetor and the engine and the lever mechanism will then be in the position shown in Fig. 10.

Mechanism controlling the advance or retard of the ignition device may be connected with the carburetor control mechanism, for example, by connecting the ignition control lever with the primary piston C or other convenient part.

Having thus described my invention, what I claim and desire to protect by Letters Patent is:

1. In a carburetor, in combination, a fuel 130

- supply device, an air inlet valve, a mixture outlet valve, separate control means for both valves, mechanism operatively connected with a moving part of the engine and 5 with the valve control means, and means controlled by the driver for varying the control means of the air and outlet valves to control automatically the relative position of the said air inlet valve and mixture 10 outlet valve to automatically provide a quality and quantity of mixture to automatically develop and maintain under varying loads the speed dictated by the position of the driver control means.
- 15 2. In a carbureter, the combination with a fuel supply device, means for controlling the air supply and means for controlling the mixture delivery, of control mechanism for the air supply means, control mechanism 20 for the mixture delivery means, means connected with a moving part of the engine for operating first one of the control means and thereafter the other control means, and hand-controlled means for varying the position 25 of the control means.
3. In a carbureter, the combination with a liquid fuel supply device, means for controlling the air supply on one side of the fuel device, and means for controlling the 30 mixture delivery on the other side of the fuel supply device, of controlling means for the air supply device, controlling means for the mixture delivery device, means operatively connected with a moving part of the 35 engine for variably operating both control means, and engine speed determining means under the control of the driver for varying the operative effect on both of the control means of the operative means connected 40 with the engine.
4. In a carbureter, the combination with a liquid fuel supply device, means for controlling the air supply on one side of the fuel supply device, and means for controlling the 45 mixture delivery on the other side of the fuel supply device, of operating mechanism for the air control means, operating mechanism for the mixture control means, means connecting both these operating 50 mechanisms, means dependent for its movement upon the speed of the engine for moving one of the operating means, and means controlling the relative movement of both operating means, also connected with 55 the engine driven member, and an engine speed determining device set by the driver and operative also upon the means for controlling the movement of both the air and mixture control means.
- 60 5. In a carbureter the combination with a fuel supply device, means for controlling the air inlet on the one side of the fuel supply and means for controlling the mixture outlet on the other side of the fuel supply, 65 of actuating means for one control device, means connecting this actuating means with a moving part of the engine, actuating means for the other control device, engine speed determining means under the control of the driver, and operatively connected 70 with the second actuating means, and means whereby the actuating mechanism of the first control device is also operative upon the second actuating means.
6. In a carbureter, the combination with 75 an air inlet valve and a mixture delivery valve, of a piston working in a cylinder, means operatively connecting the piston with the air inlet valve, a second piston working in a cylinder, means operatively 80 connecting the piston with the mixture delivery valve, a pump arranged to deliver fluid to one of the cylinders, means controlling the delivery of fluid to the second cylinder, means connecting the pump with a 85 moving member of the engine, and means under control of the driver for regulating the discharge of fluid from the second cylinder.
7. In a carbureter, the combination with 90 an air inlet valve and a mixture delivery valve, of a piston moving in a cylinder, means connecting the piston with the air inlet valve, a second piston moving in a cylinder, means connecting the piston with 95 the mixture delivery valve, a pump, means whereby the pump can deliver fluid first to one and then to the other cylinder, means connecting the pump with a moving member of the engine and a device under control 100 of the driver for regulating an outlet from the second cylinder.
8. In a carbureter, the combination with an air inlet and a mixture outlet, of a valve in the air inlet, a valve in the mixture outlet, a piston working in a cylinder, means connecting the piston with the air inlet valve, a second piston working in a cylinder, means connecting the piston with the valve in the mixture outlet, means connecting the 105 valves so that they can be operated by either piston, a pump, means whereby the pump can deliver fluid first to one cylinder and then to the other cylinder, means connecting the pump with a moving part of the 110 engine, and a device under control of the driver for regulating an outlet from the second cylinder.
9. In a carbureter, the combination with an air inlet valve and a mixture delivery 115 valve, of a piston working in a cylinder, means connecting the piston with the air inlet valve, a second piston working in a cylinder, means connecting said piston with the mixture delivery valve, a pump in direct 120 communication with the first cylinder, means operated by the first piston controlling communication between the pump and the second cylinder, means connecting the pump with a moving part of the engine, and a 125
- 65 of actuating means for one control device,

device under control of the driver for regulating an outlet from the second cylinder.

10. In a carbureter, the combination with an air inlet valve and a mixture delivery valve, of a piston working in a cylinder, means connecting the piston with the air inlet valve, a second piston working in a cylinder, means connecting said piston with the mixture delivery valve, means connecting the valves to be actuated by either piston, of a pump in direct communication with the first cylinder, means operated by the first piston controlling the supply of fluid to the second cylinder, means connecting the pump to a moving part of the engine, and a device under the control of the driver for regulating the outlet from the second cylinder.

11. In a carbureter, the combination with an air inlet valve and a mixture delivery valve, of a piston working in a cylinder, means connecting the piston with the air control valve, a second piston working in a cylinder, means connecting the piston with the mixture delivery valve, means connecting the valves to be controlled by either piston, a pump in direct communication with one cylinder, means operated by the first piston controlling communication between the pump and the second cylinder.

12. In a carbureter, the combination with means for controlling the air inlet and means for controlling the mixture outlet, of a pump, means connecting the pump with a moving part of the engine, means connecting the pump with the air inlet and mixture outlet controlling means, and means operated by the driver connected with the controlling means.

13. In a carbureter having an air inlet and a mixture outlet, the combination of a circulating pump, means operated by the driver for determining an engine speed, and means connected with the pump for automatically controlling the quantity and quality of the mixture required to develop the speed under varying loads determined by the driver.

14. In a carbureter, the combination with a pump, means connecting the pump with a moving part of the engine, and speed control means operated by the driver, of means for automatically regulating the air inlet and mixture outlet of the carbureter, means connecting the automatic control means with the pump and means connecting the control means with the speed regulating device controlled by the driver.

15. In a carbureter, the combination of a pump, means connecting the pump with a moving part of the engine, means controlling the air inlet, means controlling the mixture outlet, a cylinder, means establishing communication between the pump and the cylinder, a second cylinder, means controlling communication between the pump and

the second cylinder, means operated by the driver controlling the discharge from the second cylinder, means connecting a piston in one cylinder with the air inlet control and means connecting a piston in the other cylinder with the mixture control.

16. In a carbureter, the combination with an air inlet valve and a mixture outlet valve, of a pump, a piston working in a primary cylinder communicating with the pump, a piston working in a secondary cylinder, means operated by the primary piston controlling admission of fluid to the secondary cylinder, means operated by the driver controlling the outlet from the secondary cylinder, lever mechanism connecting the primary piston with the air inlet valve and lever mechanism connecting the secondary piston with the mixture controlling valve.

17. In a carbureter, the combination with an air inlet valve and a mixture delivery valve, of a piston working in a primary cylinder, lever mechanism connecting the air inlet valve with the piston, a piston working in a secondary cylinder, lever mechanism connecting the piston with the mixture delivery valve, lever mechanism connecting both valves with both pistons, a pump in direct communication with the primary cylinder, a valve operated by the primary piston controlling the inlet to the secondary cylinder, a valve operated by the driver controlling the outlet from the secondary cylinder, and means connecting the pump with a moving part of the engine.

18. In a carbureter, the combination with an air inlet control valve and a mixture delivery valve, of a piston working in a primary cylinder, a stop carried by the piston, a link connected with the stop, a lever bearing against the said stop, a second link connecting the aforesaid link and lever, a connection between said lever and the air inlet valve, a lever connected with the mixture delivery valve, a piston working in a secondary cylinder, a connection between the piston and the lever of the delivery valve, link mechanism connecting the lever of the delivery valve with the aforesaid stop, a pump in open communication with the primary cylinder, a valve between the primary and secondary cylinders, means connecting said valve with the primary piston, a device operated by the driver controlling the outlet from the secondary cylinder, and means connecting the pump with a moving part of the engine.

19. In a carbureter, the combination with an air inlet valve and a mixture delivery valve, of a piston working in a cylinder, a second piston working in a cylinder, a differential mechanism connecting both pistons with both valves, a pump in direct communication with one cylinder and in indirect communication with the other cylinder,

and means operated by the driver for controlling the outlet from one of the cylinders.

20. In a carbureter, the combination with
5 an air inlet valve, and a combined mixture
delivery and air by-pass valve, of a piston
working in a primary cylinder, a piston
working in a secondary cylinder, differen-
tial mechanism connecting the pistons and
10 the valves, a pump in direct communication
with one cylinder, a valve between the cyl-

inders, a connection between the valve and
the primary piston, and a valve operated by
the driver controlling the outlet from the
secondary cylinder. 15
